UNITED STATES PATENT OFFICE.

WALLACE D. JOHNSON, OF BELOIT, WISCONSIN, ASSIGNEE TO YATES-AMERICAN MACHINE COMPANY, OF BELOIT, WISCONSIN, A CORPORATION OF DELAWARE.

CHIP BREAKER.

Application filed February 25, 1927. Serial No. 170,786.

This invention relates to wood working machines, and more particularly to the chip breakers associated with the cutter heads of such machines.

5 The principal object of the invention is to provide improved means in the form of a novel air snubber for holding the chip breaker firmly against the work irrespective of changes in the position of the chip breaker occasioned by fluctuations in the dimensions 10 of the work.

Another important object is to provide improved means for effecting a quick release of the chip breaker.

15 Still another important object is to provide a multiple-part shoe for the chip breaker in which the parts are both interchangeable in position and separately reversible, whereby to permit convenient and economical maintenance of the proper surface at the greatest 20 point of wear.

Other objects and advantages of the invention will be evident to those skilled in the art upon a full understanding of the construction, arrangement and operation of the 25 improved chip breaker.

One form of the invention is presented herein for the purpose of exemplification, but it will of course be appreciated that the 30 invention is susceptible of embodiment in other structurally modified forms coming equally within the comprehensive scope of the appended claims.

In the accompanying drawing:

35 Fig. 1 is a partially sectioned plan view of a chip breaker embodying the features of the invention;

Fig. 2 is a section through the air snubber, taken on the line 2—2 of Fig. 1;

40 Fig. 3 is a side view of the multiple-part shoe; and

Fig. 4 is a perspective view of one of the interchangeable parts of the shoe.

As will be observed in the drawing, the 45 chip breaker 10 is pivoted at 11 to a matcher plate 12 in which a suitably driven cutter head is adapted to be journaled, and the plate 12 is slidably mounted on two parallel rails 13 to permit the cutter head and chip

breaker to be shifted as a unit toward or 50 away from the longitudinal axis of the associated wood-working machine. The chip breaker is held against the work, or, in the absence of any work, against a suitable stop on the matcher plate, by a resiliently yieldable air snubber 14.

The device 14—which constitutes one of the principal features of the invention—consists of a cylinder 15 which is pivoted at one end to the matcher plate, a hollow piston 16 which is positioned in the cylinder, a coil spring 17 which is compressed between the ends of the cylinder and piston, a one-way spring-pressed ball valve 18 which is positioned in a port 19 in the cylinder for permitting air to enter the cylinder to replace any air escaping therefrom past the piston, and a stem 20 on the piston having a forked end portion 21 which engages with a lug 22 on a quick release 23 which is carried by the 70 chip breaker.

The piston is limited in its outward movement by a flat ring 24 which is secured against the open end of the cylinder in overlapped relation to the closed end of the piston. The spring encompasses a rod 25 which is positioned centrally within the hollow portion of the piston, and the air chamber within the cylinder is of consequently small dimensions. The points of connection of the snubber with the chip breaker and the matcher plate, are preferably on a line adjacent the pivotal axis 11 of the chip breaker, and any pivotal movement of the chip breaker causes but a very small movement in the snubber.

When the work to be cut comes into engagement with the shoe 26 of the chip breaker, it moves the shoe backwardly about the pivotal axis 11, causing the piston 16 to move inwardly in the cylinder against the combined resistance of the spring and the air in the same. As the work passing the shoe increases or diminishes in width, the shoe moves backwardly or forwardly with the edge of the same, and the spring and air in the cylinder expand or compress in conformity therewith, any air that escapes from the cylinder past the piston being replenished

automatically through the valve 18. By means of this construction, the shoe of the chip breaker is caused to bear firmly against the work without rebound or chatter.

- 5 The quick release 23, which carries the lug 22 engaged by the stem 20 of the snubber, consists of a small circular plate 27 which is secured to the lower end of a pin 28 journaled in an aperture in the chip breaker. 10 The lug 22 is secured eccentrically to and projects downwardly from the plate 27, and a lever 29 is secured to the pin 28 above the chip breaker. The lever 29 is provided with a handle 30 on the end of the same, and, 15 when the lever is swung by the handle into the position shown in full lines in the drawing, it abuts against a stop 31 on the chip breaker and holds the lug 22 in a position past dead center relative to a line passing 20 through the pivotal axis of the pin 28 and the pivotal axis of the connection between the snubber and the matcher plate. In order to release the chip breaker from the action of the snubber, it is merely necessary to 25 swing the lever 29 away from the stop 31 into the position shown in dotted lines in the drawing, whereupon the lug 22 will be moved in an arc to a position out of engagement with the forked end portion 21 of the 30 stem 20, and the snubber may be swung into the inoperative position shown in dotted lines in the drawing.

The shoe 26 of the chip breaker is of special construction, and is composed of a 35 number of interchangeable and separately reversible wearing parts 32 which are arranged together in stacked relation in a holder 33. The holder 33 is pivoted to the chip breaker at 34, and is held in any desired position of angular adjustment relative to the same by a set screw 35 and a locking screw 36. The holder is provided at its lower front edge with a beveled lip 37 which extends freely beneath the work, and the 40 wearing parts 32 are clamped in the holder by a screw 38. The point of greatest wear on the parts 32 is at the approximate location indicated by the numeral 26, and the purpose of the special shoe construction herein described is to permit easy and inexpensive renewal of such wearing face.

Each of the parts 32 of the shoe is provided with a flat rear face 39 which fits against a similar face on the holder, and 45 with a curved front or wearing face 40 which is of the same curvature adjacent both ends. Most of the work ordinarily operated on by a cutter head is of less thickness than the combined heights of the parts 32 in the holder, and, because of this, the lower part or parts receive the greatest amount of wear. To compensate for such unevenness in wear, the position of the parts may be changed as frequently as necessary in order to maintain 50 the proper wearing face at the desired point,

and the position of any one or all of the parts may be reversed end for end with the same object in view, it being only necessary to remove the screw 38 in order to effect such re-arrangement.

I claim:

1. The combination with a movable chip breaker, of a snubber for the same characterized by a combined spring and air cushion.

2. The combination with a movable chip breaker, and a snubber for the same, of a quick release, including a cam on the chip breaker adapted to be engaged by the snubber, and means for moving the cam into a position out of engagement with the snubber.

3. The combination with a pivotally mounted chip breaker, of a resiliently yieldable snubber for the same characterized by a combined spring and air cushion.

4. The combination with a pivotally mounted chip breaker, of a snubber for the same, including a compressible air chamber, and a spring tending to distend the chamber.

5. The combination with a pivotally mounted chip breaker, of a snubber for the same, including a compressible air chamber, a spring in the chamber tending to distend the same, and a one-way valve in the chamber for permitting air to flow into the same to replace any air escaping therefrom past the piston.

6. The combination with a matcher plate, and a chip breaker pivotally mounted thereon, of a snubber connecting the matcher plate and the chip breaker and comprising a hollow cylinder connected to one of said members, a piston in the cylinder connected to the other of said members, a spring in the cylinder tending to move the piston outwardly, and a one-way valve in the cylinder for permitting air to flow into the same to replace any air escaping therefrom past the piston.

7. The combination with a pivotally mounted chip breaker, and a snubber for the same, of a quick release, consisting of a cam on the chip breaker adapted to be engaged by the snubber, and a handle connected with the cam for moving the same into a position out of engagement with the snubber.

8. The combination with a pivotally mounted chip breaker, and a snubber for the same, of a quick release, consisting of a member pivoted to the chip breaker, a lug secured to the member eccentrically of the pivotal axis of the same for engagement with the snubber in one position of the member, a stop for holding the member in that position, and a handle for moving the member into or out of that position.

9. In a chip breaker, a shoe for engagement with the work, consisting of a stack of wear subjected parts which are interchangeable with each other and are separately reversible end for end.

10. In a chip breaker, a shoe for engagement with the work, said shoe being provided with wearing faces at both ends and being reversible end for end in the chip breaker.
11. In a chip breaker, a shoe for engagement with the work, consisting of a stack of
- wear subjected parts which are provided with curved wearing faces at both ends and are interchangeable with each other and 10 separately reversible end for end.

In testimony whereof I have hereunto subscribed my name.

WALLACE D. JOHNSON.
